APPARATUS FOR HOLDING DOCUMENTS
FOR MANIFOLD WRITINGArmand Elisabeth and Germaine Brunet
Elisabeth, Brussels, BelgiumApplication December 10, 1946, Serial No. 715,226
In Belgium January 3, 1946

9 Claims. (Cl. 282—29)

1

This invention relates to document holders, more particularly to apparatus of the character indicated for holding documents intended to be slidably positioned for duplicating, such as those used for accountancy purposes and the like, and is especially concerned with improvements in devices of the type in which rulers or the like are used to insure the correct positioning of the documents relative to one another and to secure said documents in their correct positions.

For this purpose, rulers which are preferably arranged substantially parallel to one another are adapted to be raised and lowered relative to a base plate, which is generally flat, and which supports the documents. A ruler, when lowered on the base plate to hold thereon a document or documents, serves as a positioning guide for a superimposed document or documents.

Particularly in procedures involving duplication by transfer, carbon sheets are generally used for transferring to a document or documents an inscription which is traced on another superimposed document.

However, as now carried out, this procedure presents many disadvantages.

When, for example, carbons of suitable size are to be put in position below documents, on one of which inscriptions are about to be traced and thereby to be transferred to underlying documents, difficulties are generally experienced in introducing the carbons due to the tendency of the carbons to roll up and, if the carbon is thin, to become easily creased. If, on the other hand, the carbon or carbons are fixed, particularly by holding them by means of the ruler which is intended to hold the document on the base plate so as to retain freedom of movement of the document or documents superimposed thereon, correct positioning of the superimposed document or documents is prevented owing to the presence of the carbon or carbons interposed between the documents and their positioning rulers.

The object of the present invention is to provide an improved document holder whereby these disadvantages may be obviated.

According to the invention, the carbon or carbons are fixed in such manner that, while freedom of movement of each and every document is permitted, direct contact is provided between each of the documents to be positioned and its positioning ruler or guide, this direct contact being insured along a predetermined length, or at two or more spaced points, either by the cooperation of recesses provided in the rulers or guides with one or more flaps, tongues or the like pro-

2

vided on the carbon or carbons, or by the cooperation of projections on the rulers with a suitable aperture or apertures formed in the carbon or carbons.

Other features and advantages of the invention will become apparent from the following description of certain preferred embodiments, given by way of example and diagrammatically illustrated in the accompanying drawing, wherein:

10 Fig. 1 is a more or less perspective view of a document holder in accordance with the present invention;

Fig. 2 is a transverse sectional view taken on the line 2—2 in Fig. 1;

15 Fig. 3 is a diagrammatic view illustrating the operation of the holder shown in Figs. 1 and 2; and

Fig. 4 is a diagrammatic view illustrating a modified arrangement.

20 Referring first to Figs. 1 and 2, the document holder illustrated comprises a substantially flat base plate 1 adapted to support the documents on which inscriptions are to be drawn or transferred by duplicating, as for instance, accountancy documents.

Secured to base plate 1, for example along one of its lateral sides, is a mounting 2 comprising a part 3, which may be slotted as shown at 2a and which overhangs part of the base plate 1, whilst preferably extending parallel with said base plate.

25 The mounting 2 is provided with rulers 4 adapted to be moved so as to rest on the base plate 1 or to be spaced therefrom, such movements being guided by means of stirrups as shown at 5, preferably adjustable transversely to the base plate 1 and to the mounting 2 to enable the rulers 4 to be located in the required positions, conveniently parallel to one another. Stirrups 5 are secured in their adjusted positions by means of screws 6

30 and the rulers are controlled by lever cams 7 preferably in such a way that the cams effect the raising of the rulers against the action of springs 8, shown in Fig. 2 surrounding the rods 9 which connect the rulers 4 to the lever cams 7, but which may be otherwise arranged if desired, for example housed in recesses provided in the rulers at the locations of the guiding stirrups 5.

35 It will be seen that when a lever cam 7 is raised from the position shown in Fig. 1, the corresponding ruler 4 is moved away from the base plate 1, thus allowing documents to be inserted under the ruler, whereas when the lever is lowered (that is to say, brought back to the position shown in Fig. 1) the spring 8 presses the ruler 4 and the

documents inserted beneath it against the base plate 1. When lowered, a ruler 4 can be used to insure the positioning of the documents it is desired to superimpose upon the first-mentioned documents. For ensuring the positioning of a document or documents immediately adjacent to the base plate 1, no movable ruler is required and for such purpose any suitable portion of the mounting 2 may be used, for instance, the guide formed by the edge 2b of said mounting.

As thus far described, the arrangement is similar to that of known arrangements, so that a more extensive description thereof is unnecessary.

According to the embodiment of the invention shown in Figs. 1 to 3, the carbons 10 to be fixed in position comprise one or more flaps such as 11 (which may be provided in the material of the carbons themselves or if desired in a stiffer material attached to the carbons) of greater length than the overall width of the rulers and positioning guides, so as to project on either side thereof, these flaps being adapted to be secured, beyond the rulers and guides, by any suitable means.

On the other hand, the positioning rulers 4 comprise recesses 12, the positions of which correspond to the positions of the flaps 11 of the carbons 10, and the depth of which is such that the flaps 11 are perfectly free therein, thus enabling documents to be inserted under and between the carbons and into direct contact with the rulers and guides intended to be used for their positioning.

Thus, in Fig. 3, the positioning rulers 4a and 4b being raised, and a document such as 13 on which transfers are to be made being slipped on the base plate 1, under the carbons, until the positioning guide 2b is engaged, the ruler 4a can be lowered, thereby retaining the document 13 in position. A document 15 can then be either inserted between the carbons, e. g. over a carbon 16 covering the inscription space of the document 13, if the document 15 is likewise a document on which a transfer is to be effected, or the document can be placed above all the carbons, if the inscription is to be directly traced thereon, the document 15 in each case coming in direct contact with its positioning ruler 4a and being properly positioned thereby while being retained in the desired position by lowering the ruler 4b into contact therewith. When the ruler 4b is lowered, a further document 17 may be inserted between the carbons, while allowing a carbon 18 to rest directly on the document 15, or may be placed above all the carbons, the document 17 coming in any case into direct contact with the face of its positioning ruler 4b, in which position it can be fixed by lowering a further ruler for positioning or securing purpose, as the case may be. If desired, the document 17 may itself be covered with a carbon 19 upon which another transfer or inscription document may be superimposed, and so on until the upper document is reached, which in any case takes up a position above the carbons and is held by a securing ruler which may or may not be provided with recesses 12.

In order to secure the carbons by means of their flaps 11, as previously stated, any suitable means may be provided. In the embodiment shown in Figs. 1 to 3, the carbon securing means comprise piston-like elements 20 which slide in housings 21 formed in the base of the mounting 2 and secured to a common plate 22 connected by means of a rod 23 to a lever cam 24 with the

interposition of a spring or springs 25 coiled around the rod 23 or otherwise suitably positioned to press the plate 22 and the elements 20 in downward direction. Passages 26 for the flaps 11 are provided in the mounting 2 and these passages are with advantage extended to the outer edge of the mounting 2, while the flaps 11 may be made of such length that the flush position of these flaps, at the outer edge, indicates that the carbons occupy a correct position in the holder.

As will be apparent from the foregoing, any document (such as 13, 15, 17, etc.) may at any moment be adjusted along its positioning ruler or guide, or replaced, subject, of course, to the previous raising of the respective ruler holding the document, and also any rulers holding documents superimposed thereon, while the carbons remain in position and neither need to be manipulated nor displaced.

In the embodiment shown in Fig. 4, the carbons are provided with openings as at 27 corresponding to projecting parts 28 of the positioning rulers. These carbons can be held in position in the holder by any suitable means, as for instance, by means of a securing ruler such as 29, while the positioning of the document adjacent to the base plate 1 may be effected against a ruler such as 30 provided with projections such as 28. The remainder of the apparatus and the operation thereof are otherwise in accordance with what has been above described.

It will be appreciated that the invention is not limited to the embodiments more particularly described and illustrated, but that it comprises any suitable modifications or equivalents thereof falling within the scope of the appended claims.

We claim:

1. A document holder comprising a base plate adapted to receive superimposed removable documents and interposed carbons having cut away and solid portions therein, means cooperating with said base plate for positioning and securing said documents in operating positions, means cooperating with the base plate for securing the said carbons in operating positions, a mounting for supporting the said positioning and securing means with the securing means for the carbons located sidewise of the positioning means for the documents, and protrusions and recesses on said documents positioning and securing means for cooperation with the cut away and solid portions respectively of the carbons, whereby direct contact may be insured between the documents to be positioned and their positioning means.

2. A document holder comprising a base plate adapted to receive superimposed removable documents and interposed carbons having cut away and solid portions therein, means cooperating with said base plate for positioning said documents in operating positions, means movable towards and away from the base plate for securing said documents and carbons in operating positions, a mounting for supporting said positioning and securing means with the securing means located sidewise of the positioning means, and protrusions and recesses on said positioning and securing means for cooperation with the cut away and solid portions respectively of the carbons, whereby direct contact may be insured between the documents to be positioned and their positioning means.

3. A document holder comprising a base plate adapted to receive superimposed removable documents and interposed carbons having cut away and solid portions therein, means coop-

erating with said base plate for positioning and securing said documents in operating positions, and means cooperating with the base plate for securing the carbons in operating positions with the carbon securing means located sidewise of the positioning means for the documents, a mounting for supporting said positioning and securing means, said positioning and securing means including ruler like members, each having an operating surface comprising spaced portions situated substantially in one plane and an intermediate portion or portions situated in another plane or planes, to cooperate with the cut away and solid portions of the carbons, whereby direct contact may be insured between the documents to be positioned and their positioning means.

4. A document holder comprising a base plate adapted to receive superimposed removable documents and interposed carbons having cut away and solid portions therein, a set of document positioning and securing means arranged in a substantially parallel formation in cooperative relation with said base plate, means for securing the carbons arranged in cooperative relation with said base plate at one side of the document positioning means, a mounting on said base plate for operatively holding the document and carbon positioning and securing means, the document positioning and securing means including protrusions and recesses arranged to correspond with the cut away and solid portions respectively of the carbons, whereby the documents may be positioned and secured in edge-wise direct contact with their positioning means.

5. A document holder comprising a base plate adapted to receive superimposed removable documents and interposed carbons having cut away and solid portions therein, means cooperating with said base plate for positioning said documents, and means cooperating with said base plate for securing the document and carbons in position, a mounting for supporting said positioning and securing means, said positioning and securing means including a set of substantially parallel ruler like members movable towards and away from the base plate for positioning the documents and securing same in position, and at least one movable member for securing the carbons in position and located at one side of said set of ruler like members, each ruler like member having an operating surface facing the base plate and comprising spaced portions situated substantially in one plane and an intermediate portion or portions in at least another plane, the spaced portions in the said one plane being nearer the base plate and being made to cooperate with the cut away portions of the carbons whilst the said intermediate portion or portions then cooperate with a solid portion or

solid portions of said carbons, whereby direct contact between the documents to be positioned and their positioning means may be insured.

6. A document holder comprising a base plate adapted to receive superimposed removable documents and interposed carbons having cut away and solid portions therein, means cooperating with said base plate for positioning said documents in operating positions, means cooperating with the base plate for securing the carbons in operating positions, a mounting for supporting said positioning and securing means with the securing means for the carbons located at one side of the positioning means for the documents, passages in said mounting for accommodating solid portions of the carbons, said carbon securing means being arranged in cooperative relation with said passages.

7. A document holder comprising a base plate adapted to receive superimposed removable documents and interposed carbons having cut away and solid portions therein, a set of parallel rulers movable towards and away from said base plate for positioning said documents in operating positions and securing same in said positions, a mounting for movably supporting the rulers and means for moving said rulers, protrusions and recesses on the operating surfaces of the rulers arranged for cooperation with the cut away and solid portions respectively of the carbons, and means arranged sidewise of the set of rulers for securing the carbons in operating positions.

8. A document holder as in claim 7, including carbon securing means in the form of movable pistons, passages in the mounting for solid portions of the carbons, other passages communicating with the former passages in said mounting for accommodating said pistons and means for moving said pistons in and out of securing engagement with said solid portions of the carbons.

9. A document holder as in claim 7, including a document and carbon positioning guide on the mounting, a document and carbon securing ruler having a smooth operating surface arranged between said guide and the set of parallel rulers, means in the mounting for movably supporting said securing ruler, and means for moving said securing ruler towards and away from the base plate.
